UNITED STATES PATENT OFFICE.

ROBERT C. BROMLEY, OF PITTSBURG, PENNSYLVANIA.

HYDRAULIC VALVE.

SPECIFICATION forming part of Letters Patent No. 650,777, dated May 29, 1900.

Application filed June 30, 1899. Serial No. 722,400. (No model.)

To all whom it may concern:

Be it known that I, ROBERT C. BROMLEY, a citizen of the United States, residing at Pittsburgh, in the county of Allegheny and State of Pennsylvania, have invented or discovered a new and useful Improvement in Hydraulic Valves, of which the following is a full, clear, and exact description, reference being had to the accompanying drawings, forming part of this specification, in which—

Figure 1 is a central vertical section through my improved valve, the valve-piston being in the middle position. Fig. 2 is a similar view at right angles to Fig. 1, indicated by the line II II thereon and showing the valve-piston raised. Fig. 3 is a horizontal cross-section on the line III III of Fig. 1. Fig. 4 is a partial sectional view on an enlarged scale.

My invention relates to the class of hydraulic valves for controlling the flow of water under pressure, and it relates particularly to the construction and arrangement of the various chambers and ports, the piston-valve, and the packing-cups and manner of securing them in position for the purpose of preventing wear and cutting and also so as to utilize the expansive action of the fluid in the valve to prevent leakage at the joints of the valve.

Referring now to the drawings, 2 represents the main body portion of the valve, within which is mounted the hollow cylindrical valve-shell consisting of three sections 3^a, 3^b, and 3^c. The middle one of these sections, 3^b, is first inserted in position in the main case 2, which is provided with a series of internal annular grooves 3', and the metal of the valve-shell 3^b is then pressed outwardly by an expanding mandrel until the grooves are entirely filled. In this manner the section 3^b is immovably incorporated with the case, after which the interior of the shell 3^b is turned out to the finished size. Surrounding such shell are the chambers 4, 5, 6, 7, and 8, to the middle one of which, 6, leads the feed-passage 9, communicating with any source of pressure, while above and below the chamber 6 are the similar chambers 5 and 7, from which lead the passages 10 11, communicating with any suitable operative mechanism—as, for instance, the ends of a double-acting cylinder. These passages operate alternately as feed and exhaust passages, respectively, and communi-

cate through the ports of the shell 3 and of the valve either with the feed-chamber 6 and upper exhaust-chamber 4 or with feed-chamber 6 and lower exhaust-chamber 8, according to the position of the piston-valve. This valve is built up of three sections 12, 13, and 14, mounted on a stem 15, having an enlarged extension 16, against which the various sections of the valve are clamped together by nut 17 on the lower end. The upper and lower sections are provided with an outer cylindrical reversed shell 18, in the interior of which is a cavity 19, communicating with the outer surrounding valve-shell interior, and these shells 18 make a sliding water-tight fit within surrounding gaskets 20, of leather or other suitable material, clamped between the middle immovable section 3^b and upper and lower movable sections 3^a and 3^c. These upper and lower valve-sections are also provided with similar outwardly-projecting shell extensions, which abut against the gaskets 28, hereinafter referred to, and which limit the movement of the valve in either direction, thus relieving the nut 17 or flange 31 of upper gasket 28 from contact or interference. Likewise clamped between the middle sections 13 of the piston-valve and upper and lower sections 12 and 14 are the cups 21, turned inwardly and inclosing, with a water-tight fit inside the middle section 3^b of the valve-shell, the annular cavity 22.

Through the shell-sections at each of the annular chambers are a series of perforating-ports 4^a, 5^a, 6^a, 7^a, and 8^a, by which communication is had from the interior of the shell to the surrounding chambers, and vice versa.

In the normal position of the valve (shown in Fig. 1) the cups occupy a position above and below the middle ports 6^a, communicating with the feed-chamber 6, so that the pressure of the water within the cavity 22 will tend to throw the edges of the cups outwardly against the interior and close the passage against circulation. It will also be seen that in case the valve is moved up or down over the ports 6^a pressure from the outside upon the cups will fully or more than equalize the internal pressure tending to expand the cups, thus protecting them from abrasion or cutting due to pressure against the edges of the ports. When the valve is raised or

lowered, any leakage past the first cup 21 into the chamber 22 will tend to expand the other cup, thus preventing further circulation, and it will be noted that in such raised 5 or lowered position of the valve the cups have a bearing against the smooth interior of the shell.

The gaskets 20 surround the piston-valve above and below the cylinder-chambers 5 and 10 7, the pressure of the water tending to expand them against the outer shell of the end portions 12 and 14. Between the inner chambers 19 of these portions and the interior of the valve extend perforating ports 23, and it 15 will be seen that when the valve is moved in either direction pressure within the chambers 19 and outwardly through such ports 23 will act to overcome pressure tending to hold the gaskets against the valve-shell, so that 20 cutting or abrasion of the gaskets by pressure against the ports is prevented, as it is manifest that pressure tending to expand the gasket will provide a water seal until the ports 23 register with and pass the gaskets, thus 25 giving circulation through the ports 4^a or 8^a to waste-chambers 4 or 8. These chambers are connected by a by-pass port 24, and the lower chamber 8 is provided with a waste-pipe 25, leading off to any suitable discharge. 30 In the usual construction of valves of this class it is customary to mount all of the gaskets or cups upon the movable piston-valve within the piston-cylinder, thus permitting the pressure of the water to force the cups 35 outwardly against the ports during operation of the valve. This produces rapid cutting and destruction of the cups and requires their frequent renewal, thus involving serious delay and considerable expense. By equalizing 40 the pressure of the water in the manner I have described and shown I avoid these disadvantages and add greatly to the efficiency and life of the valve.

The sections 3^a and 3^c of the valve-shell 45 make a tight fit within the main case 2, and the sections, with the intervening gaskets 20, are tightly clamped together and against the stationary section 3^b by the heads 26 of the case by means of the securing-bolts, sufficient 50 intervening space being left at 27 to permit of compression of the gaskets. The securing-bolts of the heads are preferably inserted through radial slots in the flanges of the case and heads, respectively, thus permitting of 55 their easy and rapid removal without entirely unscrewing the nuts, whereby the time consumed in removing the heads for renewal of gaskets or for any other purpose is reduced to a minimum. 60 Between the heads 26 and the outer ends of the sections 3^a and 3^c are interposed packing-gaskets 28, which act in the same manner as gaskets 20 to make a water-tight joint and effectually close the ends of the valve-shell 65 sections against leakage. The gaskets 28 extend laterally beyond these shell-sections into an enlarged space 29 and are turned inwardly,

being provided with peripheral cup-shaped flanges 30. By this means any leakage escaping outwardly beyond ports 4 or 8 between the case 2 and the shell-sections 3^a or 3^c will be effectually sealed against further progress by its expansive action against the flange of the gasket. In a similar manner leakage is prevented around the piston-rod by 70 an internally-similar flange 31, which closely embraces the piston-rod, as clearly shown in the drawings, and by the pressure thereon around its outside effectually cuts off any leakage. In this manner I am enabled to dispense with the usual stuffing-box around the valve-stem, obviating the trouble and expense of renewal and adjustment of the packing and resulting in greater compactness, simplicity, and cheapness of construction of the valve. 85

Changes and modifications may be made by the skilled mechanic without departing from my invention, since I do not desire to be limited to the exact construction shown, but to include such changes within the scope of the 90 following claims.

What I claim is—

1. In a hydraulic valve, the combination of a main casing having a middle internal annular chamber in communication with a supply-passage, similar chambers at each side of such middle chamber in communication with supply and exhaust passages, additional similar chambers beyond such supply and exhaust passages, a port connecting such outer annular chambers and communicating with an exhaust-passage; an inner longitudinal shell composed of a middle immovable and outer movable sections, ports therethrough communicating with the annular chambers, inwardly-turned packing-gaskets clamped between the sections, a reciprocating piston-valve mounted within the shell having outer hollow extremities and ports therethrough and a middle annular cavity between inwardly-turned packing-cups, whereby communication is established through the ports and passages at varying positions of the valve. 105

2. In a hydraulic valve the combination of a main casing having a longitudinal chamber, a middle valve-casing secured therein by expanded annular rings, similar valve-casings movably mounted within the longitudinal chamber forming continuations of such middle casing at each end thereof, intervening inwardly-turned packing-gaskets secured between the abutting ends of such valve-casing sections, packing-gaskets at each end of such outer valve-casings, closing-heads for the main casing with means for adjusting such heads against the gasket and ends of the outer valve-casing sections, a series of annular chambers within the main casing and surrounding the valve-casing sections, ports through the valve-casing providing communication from the interior of the valve-casing to such annular chambers, supply and exhaust passages communicating with the annular chambers, a reciprocating piston- 115 120 125 130 135

valve mounted within the valve-casings having outer hollow extremities and ports therethrough, and a middle annular cavity between inwardly-turned packing-cups whereby communication is established through the ports and passages at varying positions of the valve.

3. In a hydraulic valve, the combination of a main casing having a longitudinal chamber, a middle valve-casing secured therein by expanded annular rings occupying internal annular cavities in the main casing, similar valve-casings movably mounted within the longitudinal chamber forming continuations of such middle casing at each end thereof, intervening inwardly-turned packing-gaskets secured between the abutting ends of such valve-casing sections, packing-gaskets at each outer end of such outer sections having inwardly-turned flanges projecting into cavities in the main casing, closing-heads for the main casing with means for adjusting such heads against the gaskets and ends of the outer valve-casing sections, a middle internal annular chamber surround-

ing the valve-casing and in communication with a supply-passage, similar annular chambers at each side of such middle chamber in communication with supply and exhaust passages, additional similar annular chambers 30 beyond such supply and exhaust passages constituting waste-chambers, a longitudinal external passage connecting such chambers and in communication with a waste-passage, ports through the valve-casing providing 35 communication from the interior of the valve-casing to the annular chambers, a reciprocating piston-valve mounted within the valve-casings having outer hollow extremities and ports therethrough, and a middle annular 40 cavity between inwardly-turned packing-cups whereby communication is established through the ports and passages at varying positions of the valve.

In testimony whereof I have hereunto set 45 my hand.

ROBERT C. BROMLEY.
